UNITED STATES PATENT OFFICE.

HENRY STROTHENKE, OF ST. LOUIS, MISSOURI, ASSIGNOR OF ONE-HALF
TO CHARLES F. BUSSE, OF SAME PLACE.

BARREL-BUNG.

SPECIFICATION forming part of Letters Patent No. 656,734, dated August 28, 1900.

Application filed November 20, 1899. Serial No. 737,629. (No model.)

To all whom it may concern:

Be it known that I, HENRY STROTHENKE, a citizen of the United States, residing at St. Louis, State of Missouri, have invented certain new and useful Improvements in Barrel-Bungs; and I do hereby declare the following to be a full, clear, and exact description of the invention, such as will enable others skilled in the art to which it appertains to make and use the same.

My invention relates to improvements in barrel-bungs; and it consists in the novel combination and arrangement of parts, as will be hereinafter more specifically described and claimed.

In the drawings, Figure 1 is a top plan view of my complete invention; and Fig. 2 is a vertical section of the same, taken on the line *xx* of Fig. 1.

The object of my invention is to construct a simple, durable, and practical bung for barrels which will not only hermetically seal the barrel, but is of such a nature that the faucets or vents usually employed in connection with beer barrels or kegs may be readily inserted and forced through the bung, in which operation the diaphragm which seals the bung is readily punctured and operates as a sealing-washer against the escape of the liquid contained within the barrel after the faucet or vent has been forced into position.

Referring to the drawings, 1 represents a thimble which is provided with exterior screw-threads, by means of which the thimble may be securely fastened within the bung-hole of the barrel, said thimble being provided with an annular flange 2, forming a seat for the reducing washer or collar 10, a rubber washer or gasket 11 being interposed between said collar and the annular flange 2 of the thimble, whereby the two may be hermetically sealed in respect to one another. The inner surface of the thimble 1 is also provided with screw-threads, with which the screw-threads of the collar 6 coöperate, the latter being pro-

vided with an annular groove 7, formed on the lower surface of the same, which surface is adapted to be brought into binding contact with the upper surface of the diaphragm 12, a portion of the diaphragm being forced into 50 the annular groove 7 when the parts are in their normal position, whereby the same are hermetically sealed in respect to one another. The collar 6 is provided with an annular extension 8, having an outer inclined wall, over 55 which extension a thin metallic cap 9 is adapted to be sprung, whereby the diaphragm 12 is thoroughly protected in transit and at other times before the faucet or vent is used in connection with the barrel.

The diaphragm 12 may be made of any suitable material, or such that can be easily punctured, and may consist of asbestos, paper, or any suitable textile material that may answer the purpose and which will form a packing 65 about the faucet or vent when the same are driven through the bung. It is further to be noted that the diaphragm may be formed in any suitable manner best adapted for the purpose, and therefore I do not limit myself 70 to the flat formation as shown.

Having fully described my invention, what I claim is—

A barrel-bung, comprising a thimble, an annular flange forming a part of the same, and providing a shoulder or seat, a reducing-washer located within said thimble, a suitable washer interposed between the reducing-washer and seat of the thimble, a screw-threaded collar coöperating with the inner 75 screw-threaded portion of the thimble, and a diaphragm interposed between said screw-threaded collar and reducing-washer, as and for the purpose described.

In testimony whereof I affix my signature 85 in presence of two witnesses.

HENRY STROTHENKE.
